TOY ACCORDION

Nicholas T. Baldanza, Rutherford, N. J., assignor
to Columbia Protekosit Co. Inc., Carlstadt,
N. J., a corporation of New Jersey

Application July 24, 1948, Serial No. 147,740

Term of patent 7 years

(Cl. D56—1)

To all whom it may concern:

Be it known that I, Nicholas T. Baldanza, a citizen of the United States, and resident of Rutherford, in the county of Bergen, State of New Jersey, have invented a new, original, and ornamental Design for a Toy Accordion, of which the following is a specification, reference being had to the accompanying drawing, forming a part thereof, and of which

Fig. 1 is a side view of a toy accordion, showing my new design, the bellows shown partly extended.

Fig. 2 is a top plan view; and

Figs. 3 and 4 are left end and right end views, respectively, taken on Fig. 2.

Both sides of the accordion body are similar in appearance.

I claim:

The ornamental design for a toy accordion, as shown and described.

NICHOLAS T. BALDANZA.
